UNITED STATES PATENT OFFICE

137,805

DESIGN FOR A LENS

George M. Cressaty, New York, N. Y.

Application December 13, 1943, Serial No. 111,996

Term of patent 14 years

(Cl. D48—30)

To all whom it may concern:

Be it known that I, George M. Cressaty, a citizen of France, residing at New York, in the county of New York and State of New York, have invented a new, original, and ornamental Design for a Lens, of which the following is a specification, reference being had to the accompanying drawing, forming part thereof.

Fig. 1 is a side elevational view of a lens showing my new design;

Fig. 2 is a rear elevational view thereof;
Fig. 3 is a sectional view thereof taken on line

3—3 of Fig. 2; and

Fig. 4 is a front elevational view thereof.

The dominant features of my design reside in the portions shown in full lines.

I claim:

The ornamental design for a lens, substantially as shown and described.

GEORGE M. CRESSATY.
